(No Model.)

F. H. HARRIS.
HAND RIVETING MACHINE.

No. 403,348.

Patented May 14, 1889.

Attest:

John Schuman.
P.M. Hulbert

UNITED STATES PATENT OFFICE.

FRANK H. HARRIS, OF AUBURNDALE, OHIO.

HAND RIVETING-MACHINE.

SPECIFICATION forming part of Letters Patent No. 403,348, dated May 14, 1889.

Application filed October 31, 1888. Serial No. 289,639. (No model.)

To all whom it may concern:

Be it known that I, FRANK H. HARRIS, a citizen of the United States, residing at Auburndale, in the county of Lucas and State 5 of Ohio, have invented certain new and useful Improvements in Hand Riveting-Machines, of which the following is a specification, reference being had therein to the accompanying drawings.

- 10 This invention relates to a new and useful improvement in hand riveting-machines especially designed for riveting the ends of the wire spokes of iron wheels to the rim of the wheel; and my invention consists in the peculiar construction and arrangement of the 15 different parts, whereby the machine is especially adapted for that class of work, all as more fully hereinafter described, and shown in the accompanying drawings, in which—
20 Figure 1 is a side elevation of my improved machine. Fig. 2 is a front elevation thereof, showing in dotted lines the operation of the device in connection with an iron wheel. Fig. 3 is a plan of the device detached from 25 the frame of the machine, and Fig. 4 is an inside elevation of one of the jaws of the vise.

A represents a table or bench upon which the machine is mounted.

- B is a vertical standard or frame which supports 30 the operating devices of the machine, and which is made of suitable strength, being preferably cast of iron in one piece and provided with a foot, C, by means of which it may be firmly secured by suitable bolts, D, 35 on top of the work-bench near the front edge thereof. This frame has transversely journaled in its overhanging top portion a shaft, E, to one end of which the hand-lever F is secured, while the opposite end is provided with 40 an eccentric, G. Upon this eccentric engages the eccentric-rod H, held in place upon the eccentric by means of the washer I and screw-bolt J. To the lower end of the eccentric-rod is secured the vertical reciprocating holder 45 K of the riveting-tool. This holder passes through the vertical bearing L on the standard or frame, and is provided with a socket in its lower end, in which the riveting-tool M is detachably secured in the usual manner.
50 N is a vertically-reciprocating pressure-foot centrally notched or apertured to loosely embrace the riveting-tool and vertically and

slidely secured with its shank in a suitable vertical guide-bearing, L, on the frame of the machine. The upper end of this pressure-foot is pivotally secured to one end of the lever O, which is fulcrumed to the standard, and by means of a rod, P, is connected to a foot-lever, Q, all so arranged that whenever the operator steps onto the foot-lever the pressure-foot is depressed and automatically restricted by the spring R as soon as the operator releases the foot-lever.

S is a clamp or vise horizontally and detachably secured by means of the bolts a to the 65 standard of the frame, near the foot thereof. This vise consists of a stationary jaw, b, which is bolted to the standard by the bolts a, heretofore described, and of the movable jaw c, pivotally secured to the stationary jaw by 70 means of the removable pivot-pin d. The forward ends of both the stationary and movable jaws are V-shaped, with the inner or clamping-faces vertical and parallel to each other, as shown in Fig. 2.

75 Into the forward end of each jaw is detachably secured a steel die, T, and a spring, e, placed between the stationary and movable jaws, normally operates to open the jaws by its tension. A shaft, f, is journaled transversely through the front end of the jaws and the foot of the standard, and is provided at one end with the adjusting screw-nut g and at the opposite end with the hand-lever h, screw-threaded upon the shaft, all so arranged that 80 by turning the lever to the front the jaws of the vise are closed, and by throwing it backward into the position shown in Fig. 1 the jaws of the vise are opened a sufficient distance to admit of the insertion of a wire spoke, 85 90 as more fully hereinafter described.

Below the front end of the vise is secured a suitable frame, i, provided with a central vertical slot, j, in which is slidely mounted the wheel-support U, from the face of which 95 projects a stop-shaft, V, detachably secured thereto and adapted to engage into the hub of the iron-wheels to be operated upon by the machine. This wheel-support U can be vertically raised and lowered by means of a vertical adjusting-screw, W, mounted back of the slot in the frame and having a screw-threaded engagement with a lug, k, on the rear of the wheel-support. The hand-wheel l

is provided for on the bottom of the adjusting-screw to operate the screw, and a scale or index, *m*, provided for upon the frame *i*, indicates the vertical distance from the center of the 5 stop-shaft *V* to the top of the vise.

In practice, the parts being constructed and arranged as described, the machine is designed to operate as follows: An iron wheel of the description for which the machine 10 is designed and having its wire spokes loosely engaged into the iron rim of the wheel is engaged with its hub on the stop-shaft *V* of the wheel-support, and the latter is then so adjusted as to allow the tire of the 15 wheel to rest on top of the vise to form the anvil in riveting. One of the spokes of the wheel is then engaged into the jaws of the vise between the steel dies and clamped fast therein by the operation of the lever *h*. The 20 operator then places his foot on the foot-lever *Q*, thereby forcing the pressure-foot down upon the rim of the wheel, and then, grasping the lever *f*, throws such lever forward to cause the riveting-tool to descend upon the end of 25 the spoke and thereby rivet-head it. The spoke thus finished is then disengaged from the vise and the operation repeated with the next spoke until all the spokes are operated upon in such manner.

30 My machine is especially adapted to be used for doing the work described with wheels of all sizes, and to this end the following special provision has been made in the construction of the machine:

35 First, the ready and exact vertical adjustability of the wheel-support *U* is intended to admit wheels of larger or smaller diameter by raising and lowering such wheel-support. At the same time, by means of its index, it forms 40 an accurate catch, whereby the wheel is made of the exact diameter indicated on the scale, and, moreover, is made perfectly round. By having the adjusted hand-wheel *l* at the bottom the operator can use his hands and eyes 45 simultaneously in adjusting the wheel-support.

Second, the vise forms a separate and easily-detachable frame of the machine for the purpose of exchanging it for a heavier or lighter 50 one, as the work is lighter or heavier. As in riveting the heavier spokes of larger wheels

there is necessarily a strong vise required, I provide my machine with several sizes of vises adapted to be interchangeably secured to the machine and differing in the strength and 55 form of the forward end of the jaws, the shape and form of which necessarily are conditioned by the size of the wheel and the distance the spokes are placed apart, as it is obvious that the jaws cannot be made thicker upon the 60 ends than is necessary to allow them to project through the intervals of the spokes.

By means of the adjusting-nut *g* on the shaft *f* of the vise the jaws may be adjusted to open and close within a fixed throw of the 65 lever *h* to release and clamp the spokes, thus doing away with the inconvenience of changing the normal positions of the lever *h* for spokes of different gage.

The vise ought to be constructed to give a 70 quick action, so as to require but a limited movement of the lever *h*, and any other known construction to operate the jaws may be substituted for the one shown and described.

What I claim as my invention, and desire 75 to secure by Letters Patent, is—

In a hand riveting-machine for the purpose described, the combination, with the frame *B* of the machine, of the vise *S*, detachably secured thereto and provided with a hand-lever, *h*, and adjusting-nut *g*, the reciprocating riveting-tool secured in a guide-bearing, *L*, on the frame of the machine, the actuating hand-lever *F* and its connections with the riveting-tool, the reciprocating pressure-foot *N*, secured 85 in vertical guide-bearings of the frame, the actuating foot-lever *Q* and its connection with said pressure-foot, the frame *i*, provided with the vertical slot *j* and index *m*, the wheel-support *U*, slidingly mounted in the slot of the 90 frame *i* and provided with the adjusting-screw *W*, having the hand-wheel *l*, and the stop-shaft *V*, carried by the wheel-support *U*, all combined to operate substantially as described. 95

In testimony whereof I affix my signature, in presence of two witnesses, this 14th day of September, 1888.

FRANK H. HARRIS.
